UNITED STATES PATENT OFFICE.

EDWARD HUEBNER, JR., OF DETROIT, MICHIGAN, ASSIGNOR OF ONE-HALF
TO GEORGE C. HUEBNER, OF SAME PLACE.

SCREEN-DOOR.

SPECIFICATION forming part of Letters Patent No. 245,069, dated August 2, 1881.

Application filed January 31, 1881. (No model.)

To all whom it may concern:

Be it known that I, EDWARD HUEBNER, Jr., of Detroit, Wayne county, Michigan, have invented an Improvement in Screen-Doors, of 5 which the following is a specification.

The nature of this invention relates to certain new and useful improvements in the construction of screen-doors; and the invention consists in the peculiar mode of constructing 10 the frames and parts of doors or windows for receiving screens, as more fully hereinafter set forth.

Figure 1 is an elevation with the moldings of one panel removed. Fig. 2 is an enlarged 15 cross-section.

In the drawings which form a part of this specification, A represents the stiles of a door, B the rails, and C the wire-screen panels, which are secured in place as hereinafter set forth.

20 In forming the stiles and rail I first pass the stick through a proper machine, which "sticks" upon one edge the molding a, and after this is done the stick is presented to a proper machine, which saws out such molding, the shoulder b thereby being left, and in which is then 25 cut the channel c in such shoulder. After the stiles and rails have been thus formed they

are put together in the desired form of a door. The wire-cloth is then put in place, the edges being turned down into the channels c, after 30 which a strip, d, is inserted and glued or otherwise secured in place, filling the channel flush with the shoulder. The molding a is then put in place and secured by brads.

By this construction I produce a screen-door 35 which is neat in appearance, all the rough work being hid by the molding.

It is evident that this construction can be advantageously adapted in the manufacture 40 of window-screens.

What I claim as my invention is—

The mode herein described of constructing door or window frames for receiving netting, consisting in "sticking" the stiles and rails to produce upon one edge a molding, a, which is 45 then removed to leave a shoulder, b, in which a channel is cut for receiving the edge of the netting and the fastening-strips, the molding, removed as described, being used to cover the fastening-strip, substantially as specified.

EDWARD HUEBNER, JR.
